UNITED STATES PATENT OFFICE.

BENJAMIN DAVIES, OF BROOKLYN, ASSIGNOR TO L. STRAUS & SONS, OF NEW YORK, N. Y.

DESIGN FOR THE ORNAMENTATION OF GLASS VESSELS.

SPECIFICATION forming part of Design No. 23,252, dated May 8, 1894.

Application filed April 5, 1894. Serial No. 506,505. Term of patent 7 years.

To all whom it may concern:

Be it known that I, BENJAMIN DAVIES, of Brooklyn, in the county of Kings and State of New York, have invented and produced a new and original Design for the Ornamentation of Glass Vessels, of which the following is a specification, reference being had to the accompanying drawings, in which—

Figure 1—is a plan view of a dish ornamented with my design, and Fig. 2—represents a cross sectional view of the same.

The leading feature of my design consists of a series of grooves starting from the center and curving outward first in one direction and then in the opposite direction until the end approximately joins the convex side of the first curve.

In the design as represented in the accompanying drawings the deep grooves A extend outward from the center of the vessel and are curved first in one direction and then in the opposite direction until each groove incloses a substantially circular field at its outer end, each of said grooves having the appearance of an interrogation mark when viewed from one side or the other of the vessel. The grooves are arranged in pairs, each pair having their direction opposite to each other, thus forming spaces between their inner curves which are.

alternately bounded by two lines relatively 30 concave, and by four lines which are relatively convex. In each of the former spaces is a spray of deep grooves B and fine grooves b, and in each of the four sided spaces is a star figure C. One half of the circular spaces 35 already described are occupied, each of them, by a design composed of a series of radiating leaf-shaped fields D of fine crossed grooves bounded by medium depth grooves d, and between the outer ends of the said 40 fields are sprays of grooves or fan figures d'. In the circular space between each two of those just described, is another design composed of four deep grooves e meeting each other and the groove A, fern figures e' of fine 45 grooves in the spaces between the grooves e and A and a small central star e².

Having thus described my invention, what I claim is—

The design for the ornamentation of glass 50 vessels substantially as herein shown and described.

In testimony whereof I affix my signature in the presence of two subscribing witnesses.

BENJAMIN DAVIES.
